US00D547263S

(12) **United States Design Patent** (10) **Patent No.:** **US D547,263 S**
(45) **Date of Patent:** **** Jul. 24, 2007**

(54) **BATTERY PACK**

(75) Inventor: **Masaki Suzuki**, Yamagata (JP)

(73) Assignee: **Top Notch Toys Ltd. Co.**, Harbor, TST (HK)

(**) Term: **14 Years**

(21) Appl. No.: **29/261,081**

(22) Filed: **Jun. 7, 2006**

(51) **LOC (8) Cl.** **13-02**

(52) **U.S. Cl.** **D13/103**

(58) **Field of Classification Search** D13/102-106, D13/110, 118-119, 184; 429/96-100, 163, 429/176

See application file for complete search history.
